Primary Examiner — Leah Macchiarolo

Assistant Examiner — Christina Gabrielle Cosden

(57) **CLAIM**

The ornamental design for a lock as shown and described.

DESCRIPTION

1.1 is a front view of the lock, showing my new design;
1.2 is a back view thereof;
1.3 is a left view thereof;
1.4 is a top view thereof;
1.5 is a front, top, left side perspective view thereof;
1.6 is a left side perspective view of another state of the lock thereof, with the lock part rotated;
1.7 is a top side perspective view of another state of the lock thereof, with the lock part rotated; and

(Continued)

1.8 is a bottom view thereof.

The broken lines shown in the drawings depict portions of the lock that form no part of the claimed design.

1 Claim, 8 Drawing Sheets
